UNITED STATES PATENT OFFICE.

JACOB HIRSHFELD, OF NEW YORK, N. Y.

OUTING-BELT.

SPECIFICATION forming part of Letters Patent No. 439,244, dated October 28, 1890.

Application filed August 2, 1890. Serial No. 360,786. (No model.)

To all whom it may concern:

Be it known that I, JACOB HIRSHFELD, a citizen of the United States, residing in the city, county, and State of New York, have invented 5 certain new and useful Improvements in Outing-Belts, of which the following is a specification.

My invention is a combined sash and outing-belt constructed to permit the sash to be 10 quickly and neatly secured in proper position to cover the belt without tying the sash or the necessity of constantly refolding the same, as fully set forth hereinafter, and as illustrated in the accompanying drawings, in which—

15 Figure 1 is a perspective view of my combined sash and outing-belt, showing the ends disconnected; Fig. 2, an exterior view showing the same as arranged when in position around the body of the wearer.

20 A represents an ordinary waist-belt of any suitable width and material, provided at the opposite ends with buckles 2 2, eyes 3 3, and a coupling-hook 4, by means of which it may be lengthened or contracted to proper size 25 and then fastened around the waist of the wearer. Such waist-belts have become a necessity in supporting the clothing for outdoor work and sport, but are objectionable in consequence of their unsightly appearance, for 30 which reason it is common to conceal them by a sash wrapped round the body over the belt and tied or pinned in place.

The necessity of frequently folding, tying, and untangling the sash soon impairs the appearance of the latter, while many find it difficult 35 to fold the sash in such a manner and tie it properly, and I therefore have devised a means of supporting a covering-sash in its folded position, as follows: The sash B is 40 folded longitudinally, as required, and one end 6 is plaited to reduce its width, and is then applied to the belt and turned over the opposite edges of the latter and stitched thereto along the line x. The sash is then carried 45 farther around the belt for a little over half its length, the edges 7 8 being folded in

against the inner face of the belt, as shown in Fig. 1, and another line of stitches y fastens the sash to the belt at a point adjacent to one side of the wearer, leaving the remaining portion 9 of the sash, which is about one-half of the entire length, free from attachment with the belt. The free portion 9 of the sash is contracted at the outer end and provided with a hook or other fastening 10 to engage an eye or other fastening 12, arranged adjacent to the line of stitching x. The sash and the belt are thus permanently combined with a portion of the belt enveloped in the sash, and when the belt is buckled upon the wearer the free end of the sash can be drawn around in front and secured by the fastening in the position shown in Fig. 2. As thus secured, the entire length of the belt is covered by the sash, the free portion of which hangs 65 gracefully, covering a width much greater than that of the belt in the same manner as it would if it were separate from the belt. Inasmuch as the sash is permanently plaited and fastened, it requires no care in adjustment on the part of the user.

The sash may be of any suitable width and of any desired color and material, and when necessary it can be readily removed from the belt by ripping the stitches x y and as readily 75 replaced by restitching at the same points.

Without limiting myself to the precise construction and arrangement of parts shown and described, I claim—

A combined sash and outing-belt consisting 80 of a waist-belt and a sash secured thereto at one end and at an intermediate point and having a loose end provided with a fastening device for securing it to the fixed end of the sash, substantially as described.

In testimony whereof I have signed my name to this specification in the presence of two subscribing witnesses.

JACOB HIRSHFELD.
